UNITED STATES PATENT OFFICE

GEORGE B. JOHNSON, OF EVANSTON, ILLINOIS

HYDROCARBON BURNER

Application filed September 6, 1927. Serial No. 217,685.

This invention relates to hydrocarbon burners, and more particularly to a new process and apparatus whereby fuel oil may be vaporized and mixed with air in the proper proportions, without the decomposition of the oil into its hydrogen and carbon elements so as to avoid the deposition of carbon in the vaporizer and so as to enable the fuel mixture to burn completely without residue.

10 In general terms, the apparatus includes a retort or vaporizer to which the oil is fed in quantities which vary according to the degree of heat required at the main burner. The air is forced under low pressure into and 15 through the retort by means of a motor driven fan, this air mixing with and carrying away in suspension the vaporized fuel, the combustible mixture passing directly to the burners. The conduits leading from the 20 fan to the retort and from the retort to the burners are large and unobstructed, there being nothing to impede the flow of the gaseous materials and to become clogged with carbon deposits. An auxiliary burner is provided to heat the retort, this burner being fed with combustible mixture by means of a 25 branch pipe leading from the conduit which carries the air and vaporized oil from the retort to the main burner. The passage leading to the auxiliary burner is so designed that the heat applied to the retort by this burner will never be more than sufficient to vaporize the oil without decomposing the same. An auxiliary burner supplied with fuel from 30 a separate source is provided for furnishing additional heat to the vaporizer or retort when necessary, this latter burner being automatically controlled by the temperature in the vaporizer.

40 The principal object of this invention is to provide an improved apparatus adapted to function as hereinabove briefly described, and as described more in detail hereinafter.

Another object is to provide improved means for preheating the air prior to its introduction into the retort or vaporizer.

Another object is to provide improved means for forcing air under pressure through the retort and to the burners.

50 Another object is to provide improved

means for automatically regulating the heat applied to the vaporizer, such means comprising burners fed from separate sources of supply, and thermostatically controlled by the temperature in the vaporizer.

Numerous other objects and advantages of this invention will be more apparent from the following detailed description of one approved form of apparatus utilizing the principles of this invention.

In the accompanying drawings:

Fig. 1 is a side elevation of the assembled apparatus.

Fig. 2 is a plan view of the assembled apparatus, partially broken away.

Fig. 3 is a transverse vertical section taken substantially on the line 3—3 of Fig. 1.

Fig. 4 is a horizontal section taken substantially on the line 4—4 of Fig. 3, and

Fig. 5 is a partial vertical section taken substantially on the line 5—5 of Fig. 1.

While this improved burner is adaptable for various uses, the preferred embodiment of the invention herein disclosed is designed particularly for installation in home-heating furnaces, for burning oil in lieu of the coal for which the furnace was originally designed. A portion of the apparatus, including all burners, is positioned within the firebox, while other portions of the apparatus are positioned outside of but adjacent the furnace, the connection pipes being few and of small size so that they may be easily installed. The main burner may take various forms and be of various sizes and proportions, according to the capacity of the furnace and the space available within the fire-box. As here shown, the furnace walls are indicated at 1, and the main burner comprises a plurality of pipes 2 provided with slits in their upper faces. These pipes are mounted upon and are in communication with a manifold 4 which supplies the combustible mixture to the burner pipes 2.

The vaporizer or retort 5 consists of a metallic vessel closed except for the oil and air inlets and outlets hereinabove specified. The oil is supplied through a pipe 6 sealed into one end of the retort. The pipe 6 as here shown is much larger than is necessary

for the comparatively small flow of oil to the retort, the pipe being of this increased size since it serves to house the thermostat hereinafter described. The pipe 6 is provided 5 with suitable valves, hereinafter described, for controlling the amount of oil fed to the vaporizer. Only sufficient head or pressure on the oil is necessary to insure a flow into the vaporizing chamber 5. Air under low 10 pressure is continuously supplied by means of a suitable air fan or pump 7, the shaft 8 of which is connected through coupler 9 with a suitable rotary motor 10. Air under low super-atmospheric pressure (for example 15 about four ounces per square inch) is forced by the fan 7 through pipe 11 into the retort or vaporizer. It will be noted that a portion 12 of this air pipe 11 passes horizontally along and closely adjacent to one side of 20 the vaporizer 5, loops around the far end of the vaporizer as indicated at 13, extends back along the other side of the vaporizer at 14, parallel with the portion 12, and then opens into the side of the vaporizer at 15, 25 adjacent the end 16, through which the oil is admitted. The opening or port 15 is large and unobstructed, having approximately the same cross sectional area as the air pipe 11.

30 The outlet pipe or conduit 17 leads from the other end 18 of the vaporizer (opposite to the end through which the oil and air are admitted), then curves back over the vaporizer and connects with the manifold 4. The 35 outlet pipe 17 is, like the air inlet pipe 11, in free and unobstructed communication with the retort 5, and serves to conduct the combustible mixture from the retort into the manifold 4 and thence to the burners 2.

40 A branch pipe 20 leads from the fitting 19 by means of which the conduit 17 connects with manifold 4. This branch pipe 20 leads down to and supports a pair of auxiliary burners 21 located beneath the retort, these 45 burners being similar to but smaller than the main burners 2, hereinabove described. It will be apparent that the branch pipe 20 supplies a portion of the combustible mixture generated in the retort 5 to the auxiliary 50 burners 21 which serve to heat the retort. A butterfly valve 22, thermostatically operated as hereinabove described, is positioned in the downwardly extending branch of supply pipe 20, but the auxiliary burners 21 and the 55 conduits leading thereto are preferably so designed and proportioned that the heat applied to the retort by these burners will normally be approximately sufficient, when this valve 22 is opened, but no more than 60 sufficient to vaporize the oil delivered to the retort without decomposing same.

65 A third auxiliary burner, comprising a perforated pipe section 23 closed at one end, is positioned midway between and parallel with the auxiliary oil burners 21. This burn-

er 23 is adapted to burn gaseous fuel from a separate source of supply. As here shown, pipe 23 leads out through the wall of furnace 1 and connects thru the usual air intake valve 24 and suitable pipe fittings with the pipe 25 leading from the outside gas supply. A thermostatically operated valve 26 in pipe 25 controls the flow of gas to the auxiliary burner 23. This valve 26 is controlled by a thermostat which is mounted within the retort 5 and extends out through the end 16 of the retort, being housed within the oil supply pipe 6 as hereinabove described. The thermostat as here shown comprises a metallic tube 27 closed at its inner end and housing a carbon rod 28. When the tube 27 is heated it expands and permits the rod 28 to be pushed further into the retort by means of a spring (not shown) located outside of the furnace. When the retort and tube 27 cool off, the tube 28 will contract and push the carbon rod 28 out of the retort. A push-rod 29 connected with and operated by the carbon rod 28 serves to open or close the gas-supply valve 26 in the well-known manner. The short arm of a lever 30, intermediately pivoted at 31 on a portion of the housing of valve 26, is connected with and actuated by rod 29. The longer arm of lever 30 is connected through link 32 with the operating crank 33 on the butterfly valve 22 in pipe 20. When the thermostat expands sufficiently it will close the valve 26, which is however so adjusted that a slight flow of gas will always pass through the valve to keep burner 23 supplied sufficiently to serve as a pilot light, and also to furnish gas through the branch pipes 34 to the pilot light 35 positioned adjacent the main burner 2. The gas supply can be completely shut off by means of the manually 45 operated valve 36 positioned in pipe 25 above the thermostatically controlled valve 26. The butterfly valve 22 will be partially closed when the thermostat has expanded to its normal operating temperature, but this valve 50 will in this adjustment permit the passage of sufficient fuel to the burners 21 to provide the necessary heat for vaporizing the oil within the retort. Should the temperature in the retort fall below the desired minimum, 55 the resulting movement of the thermostat will serve to open wider the valve 22 and admit more fuel to the auxiliary burners 21.

60 The main control valve 37 for the oil supply is located in the oil feed pipe 38 which leads down to and connects into the oil supply pipe 6 previously described. This control valve 37 is regulated by the lever 39 secured to the valve stem 40. An adjusting screw 41, adapted to contact with a fixed stop 42, may be set to limit the closing of the valve so that sufficient oil will always flow to the vaporizer to furnish the minimum of fuel which will keep the burners 2 and 21 in operation. The valve control lever 39 may be provided with

an adjustable weight 43, tending to close the valve, and for automatically controlling the valve a chain or other flexible connection 44 leads from the outer end of lever 39 to a suitably positioned thermostatic motor 45. Thermostat 45 may be adjusted in the well-known manner so that when the temperature in the building falls below the desired minimum, the valve 37 will be opened to permit more fuel to flow to the vaporizer. A branch chain 46 leads from lever 39 to the control lever 47 for a damper 48 positioned in the outlet of fan 7 leading to air supply pipe 11. In this way, the amount of air delivered to the vaporizer may be varied in accordance with the supply of oil delivered thereto. The oil supply valve 37 may be manually operated, or any suitable type of manually operated control valve can be substituted for the automatically controlled valve here shown.

A second automatically controlled valve 49 is provided in the oil supply line 38 for shutting off the flow of oil to the retort 5 in case the flame should be extinguished at the burners, thus permitting the combustible mixture to return to liquid form, and stopping the further vaporization of oil delivered through inlet 6 to the retort. In any such event the oil accumulating in the retort will flow out through the air supply pipe 11 which may incline slightly downward toward the fan 7. Adjacent the inlet end of pipe 11 is a fitting 50 housing a siphon loop which will fill with oil and from which oil will spill through spout 51 into the hanging receptacle 52. The siphon in fitting 50 will normally be filled with oil so as to prevent the loss of air pressure through these pipes in the normal operation of the air supply fan 7. The valve 49 is controlled by a bellcrank lever 53, from one arm of which the receptacle 52 is suspended by means of chain or other flexible connections 54. The other arm of bellcrank 53 carries an adjustable weight 55 adapted to normally counterbalance the weight of the empty receptacle 52. When the oil condenses, or fails to vaporize in the retort, it flows back through pipe 11 and the siphon 50 and spills into the receptacle 52 which will then overbalance the counter-weight 55 and swings this weight over to the other side of the vertical so as to close the shut-off valve 49 and prevent the further flow of oil to the retort.

As hereinabove noted, the air pipe 11, before delivering its air at 15 into the vaporizer, passes almost completely around the vaporizer as indicated at 12, 13 and 14. A shield or deflector 56 is mounted above the retort 5, and has side members 57 extending down over the horizontal branches 12 and 14 of the air pipe 11. It will thus be noted that the heated gases delivered by auxiliary burners 21 and 23 to the vaporizer 5 must in order to escape flow out through the ends

of the deflector 56 or down beneath the side flanges 57, so that all of the branches 12, 13 and 14 of the air supply pipe are positioned within the path of these heated gases so that the air is preheated before entering the retort to such a temperature that it assists materially in the vaporization of the oil and in the formation therewith of the combustible mixture. It will be noted that the conduits 17 and 20 which convey the combustible mixture from the retort to the various burners are also subjected to the flow of heated gases from beneath the deflector 56 so that the combustible mixture is not permitted to lose its efficiency by cooling off while passing through these conduits.

In starting the operation of this apparatus, the gas valve 36 is turned on and the pilot light 35 and auxiliary burner 23 are ignited. Obviously, at this time the thermostatically controlled valve 26 will be open since the retort 5 is cold. Burner 23 will very soon heat the retort 5 nearly to the desired temperature, and control valve 37 is now opened to permit a flow of oil to the retort. This oil will be vaporized and mixed with the air supplied by fan 7, which has been preheated before entering the retort, and the combustible mixture will flow to the main burner 2 and auxiliary burners 21, which will be ignited by the pilot light 35 and the auxiliary burner 23 respectively. With the burners 21 in operation, the retort will quickly be brought to its normal operating temperature (about 700° Fahrenheit), whereupon the thermostat will practically shut off the flow of gas to the auxiliary burner 23 which thereafter acts normally merely as a pilot light. However, to avoid overheating the retort 5, the auxiliary burners 21 and the conduits leading thereto are so designed that they will deliver hardly more than sufficient heat to the retort to vaporize the oil, the flow of vaporized fuel to these burners being further controlled by the valve 22, and in case the temperature in the retort falls materially below that required for vaporizing the oil, and the automatic opening of valve 22 does not cause sufficient heat to be supplied by burners 21, the thermostat will contract and permit a flow of gas to the auxiliary burner 23, which will supply the necessary additional heat for bringing the retort or vaporizer up to the proper temperature.

When greater heat at the furnace is required, the oil supply valve 37 will be opened, either manually or automatically by means of thermostat 45, to permit an increased flow of oil to the vaporizer. This will increase the rate of production of vaporized oil, and there will be an increased flow of gaseous fuel to the auxiliary burners 21 as well as to the main burner 2, thereby normally furnishing the additional heat required for vaporizing the increased quantity of oil. However, if suffi-

cient vaporizing heat is not furnished by burners 21, the gas burner will automatically be brought into action to supplement the heat applied to retort 5. As before stated, 5 the damper 48 will be automatically opened in accordance with the opening of oil supply valve 37, so as to permit an additional supply of air from fan 7.

It will be noted that the preheated air is 10 forced under pressure into the retort adjacent the point of entry of the oil, and thence passes throughout the length of the retort before emerging therefrom. The fact that the air is supplied through the side of the 15 retort also causes a whirling and circulation of the air therein so that there is a complete mixture of all of the gaseous materials within the retort, and the continuous and forced circulation of air through the retort tends 20 to clean out all materials that might otherwise be deposited therein. Since the air is introduced from the side, at right angles to the incoming oil, it will flatten out the oil stream and spread it over the inner surface. 25 of the retort whereby a practically instantaneous vaporization of the oil is accomplished. Experience has shown that the retort 5 will remain clean and there will be practically no deposit of carbon or other resin 30 due therein.

The entire apparatus is simple and easily assembled and installed, and those portions of the apparatus located within the furnace and subjected to heat, include merely open 35 chambers or pipe connections, there being no restricted valves or orifices to become clogged or carbonized.

I claim:

1. In a fuel oil burner, a main burner, a 40 retort, means for feeding oil directly into the retort, means distinct from the main burner for heating the retort, means for forcing air under pressure into one end portion of the retort through the retort and from the other end 45 portion of the retort to the main burner and means controlled by the temperature in the retort for regulating the amount of heat applied to the retort.

2. In a fuel oil burner, a vaporizer, means 50 for supplying oil thereto, a burner for heating the vaporizer, a main burner, and means for forcing air under pressure to and into the vaporizer adjacent one end thereof, conduits leading from the opposite end portion of the 55 retort to both of the burners, an additional burner for heating the vaporizer, means for supplying this burner with fuel from an independent source, and means controlled by the temperature in the vaporizer for regulating 60 this additional burner.

3. In a fuel oil burner, a vaporizer, means 65 for supplying oil thereto, an auxiliary burner for heating the vaporizer, a main burner, an outlet conduit in open communication 70 with the vaporizer and leading to the main

burner, a source of air under pressure, and a conduit leading from this source and in open communication with the vaporizer at a position spaced from the outlet conduit, the latter conduit having a portion positioned in proximity to the vaporizer and auxiliary burner whereby the air will be preheated before entering the vaporizer.

4. In a fuel oil burner, a vaporizer, means 75 for supplying oil thereto, an auxiliary burner for heating the vaporizer, a main burner, an outlet conduit in open communication with the vaporizer and leading to the main burner, a source of air under pressure, and a conduit leading from this source and in open communication with the vaporizer at a position spaced from the outlet conduit, the latter conduit being looped about the vaporizer before communicating therewith whereby the air will be preheated before 80 entering the vaporizer.

5. In a fuel oil burner, a vaporizer, means 85 for supplying oil thereto, an auxiliary burner positioned beneath the vaporizer, a main burner, an outlet conduit in open communication with the vaporizer and leading to the main burner, a source of air under pressure, a conduit leading from this source and passing along both sides of the vaporizer and then communicating with the vaporizer to discharge the air thereinto at a position spaced 90 from the outlet conduit.

6. In a fuel oil burner, a vaporizer, means 95 for supplying oil thereto, an auxiliary burner positioned beneath the vaporizer, a main burner, a conduit in open communication with the vaporizer and leading to the main burner, a source of air under pressure, a conduit leading from this source and passing 100 along both sides of the vaporizer and then communicating with the vaporizer to discharge the air thereinto, and a deflector positioned above the vaporizer to cause the hot gases from the auxiliary burner to flow about 105 the last mentioned conduit and preheat the air.

GEORGE B. JOHNSON.
